UNITED STATES PATENT OFFICE

JEAN B. DAUDELIN AND EVARISTE E. TALBOT, OF FALL RIVER, MASSACHUSETTS

SHUTTLE

Application filed July 28, 1930. Serial No. 471,190.

This invention relates to shuttles and particularly to automatic threading shuttles and specifically to means for effecting the threading thereof and retaining the thread in the shuttle eye during the run of the loom.

Heretofore it has been impossible to produce an automatic threading shuttle equipped with a bobbin in which the filling was left hand wound which gave any degree of satisfaction in operation. The shuttle equipped with a right hand wound bobbin though better also was far from perfect, the difficulty in both cases lying in the continuous looping of the thread as it was fed through the shuttle eye and also in the breaking of the thread during the run. Of all automatic threading shuttles used approximately 75% have right hand wound bobbins and about 25% left hand wound bobbins. In some mills it has proven so difficult to use an automatic shuttle with a left hand threaded bobbin that the batteries were taken off and hand threading was resorted to in order to secure a satisfactory left hand run.

The features of improvement of our present invention are capable of use in shuttles having either right and left hand wound bobbins, and in either case equally fine results are produced and "ballooning" and like threading actions during the threading and run of the shuttle are practically entirely avoided. The thread is held under equal tension throughout the entire run and once in the shuttle eye escape therefrom is impossible.

These advantages and improvements over the prior art we secure by redesigning the threading end of the shuttle and the utilization therein of novel thread guide and guard members useful both during the threading and the run of the shuttle. As these members may be made of wire, the cost of production of the shuttle is considerably reduced. The construction and operation of our shuttle will be more fully disclosed in the specification which follows:

In the drawings we have shown as an illustrative embodiment a shuttle threading and thread guiding and guarding equipment which not only illustrates the principles in-

volved, but is itself a form proven satisfactory in practice and well adapted to the requirements of manufacture. Throughout the specification and drawings like reference numerals are employed to indicate corresponding parts.

In the drawings:

Fig. 1 is a view of the threading end of a shuttle of standard type equipped for a left hand wound bobbin in accordance with our invention and showing the shuttle threaded.

Fig. 2 is a side view thereof.

Fig. 3 is a plan of the frame of the shuttles, the guides being removed.

Fig. 4 is a section on the line 4—4 of Fig. 1. 65

Fig. 5 is a view similar to Fig. 1, the casing wall being partly broken away to show the thread guides and guard in position therein.

Fig. 6 is a detail of the eyelet guide. 70

Fig. 7 is a detail of one of our thread guiding guards used with a left hand wound bobbin.

Fig. 8 is a similar view of an auxiliary thread guiding guard used therewith. 75

Fig. 9 is a view of the threading end of a shuttle equipped for a right hand wound bobbin.

Fig. 10 is a section on the line 10—10 of Fig. 9, and 80

Fig. 11 is a detail of the thread guide used with a right hand wound bobbin.

The shuttle 1 may be of any standard construction having a bobbin chamber 2 in which is located a bobbin 3. From the forward end 85 or throat 2¹ of the bobbin chamber 2 leads the thread delivery eye 4 to which the threading slots 5 and 6 connect. The slot 6 connects the slot 5 with the eye 4.

In order to guide and direct the filling 90 both during the threading operation and subsequently in the run of the shuttle, we place forwardly of the bobbin in the throat 2¹ and adjacent the threading slots 5 and 6 certain instrumentalities which so combine and cooperate with each other as to secure this result regardless of direction of travel of the shuttle at the moment when the threading action occurs.

We cause the shuttle body adjacent and 100

above the threading eye to be cut away as indicated at 7 to provide a shoulder on which the thread lies during the threading action before the travel of the shuttle is reversed and the thread drawn into the eye 4. Through this shoulder passes a snubbing post 8, which traverses the thread receiving slot 9 which extends as a lateral undercut from the threading slot 5 into the wood of the counter-sunk portion or shoulder 7 rearwardly of the shuttle eye (see Fig. 3).

When the shuttle is to be used with a left hand wound bobbin, rearwardly of the shoulder 7 and adjacent the slot 9, we dispose 15 of a member A which acts as a combined thread guide during the threading operation and guard to prevent the escape of the thread once the shuttle is threaded. The member A is a piece of wire of standard gauge bent upon 20 itself to provide a vertical or upright portion A¹ having a loop A², the outer edge of which lies in a notch 10 in the rear wall of the shuttle so that during the threading operation there is no possibility of the thread 25 entering rearwardly of the member A. The member A extends outwardly from said slot 10 as at A³ and then turns and extends forwardly in a straight line as at A⁴ to a point forward of the shuttle eye 4 and inwardly 30 of the point of joinder of the threading slots 5 and 6 where it again turns outwardly as at A⁵ and enters the wood of the casing where it is anchored against dislodgment. At this point the side and upper walls of the 35 shuttle nose are cut away as at 11 to permit the thread to slide over and under the forward portion A⁴ of said guide A.

On the opposite wall of the shuttle nose approximately directly opposite the groove 10 40 is anchored our second thread guide and guard member B (Fig. 5). This member B comprises a circular anchoring portion B¹ through which passes a screw 12 which passes through the shuttle wall and acts as a reinforcement therefor. Forwardly of the screw the member B lies in a groove or channel 13 in the edge of the wall of the shuttle body on the side of the threading slot 5.

This portion B² of the member B is curved 50 inwardly as it progresses outwardly and lies slightly above and to one side of the portion A⁴ of the guide A so as to leave a narrow thread passage between the members A and B. The portion B² extends forwardly beneath the overhanging wall 11 of the shuttle to the point where the threading slots 5 and 6 join. At this point it turns inwardly and follows the wall of the shuttle along the slot 6 in a continuation 13¹ of the groove 13 until 55 it is bent inwardly at right angles as at B³ where it is driven into the wood of the shuttle body above the slot 6.

In the case of a right hand wound bobbin, the shuttle may be satisfactorily threaded 60 and the thread maintained in the eye by a

metal guide R (see Fig. 11) which is anchored at the rear end R¹ in the shuttle wall beneath the threading slot 5 and adjacent the shoulder 7. The guide R is bent so that a portion R² extends across the shuttle throat just rearwardly of the shoulder 7 where it turns forward as a portion R³ and extends throughout the slot 5 beneath the overhanging wall 11 until that slot joins the slot 6 at which point it turns as at R⁴ and follows the wall of the slot 6 until it enters and is anchored as at R⁵ in the shuttle wall.

Just beneath the bend where the portions R² and R³ meet there is anchored in the floor of the neck a vertical guide S which is bent outwardly and has its upper end S¹ disposed in the slot 10 in the shuttle wall. This guide S with a right hand wound bobbin tends to maintain the thread in the slot 9 during the run of the shuttle and lead it thereinto during the threading operation.

Forwardly of the bend in the member B and the joinder of the thread passages 5 and 6, the shuttle nose is grooved outwardly as at 11' (Figs. 2 and 3) to permit the thread to be drawn forward in a straight line before the same is carried down and back through the passage 6 into the eye 4.

An eyelet member or thread guide C which is made of metal wire is bent at its end C¹ to conform to the curvature of the eyelet 4 and is mounted in the shuttle with the eyelet end disposed adjacent the thread outlet and its other end penetrating and passing entirely through the shuttle in front of the thread outlet and beneath the slot 6 as at C² to reinforce the same. As the free end of the member C is disposed in the thread eyelet inwardly of the body of the wire, it not only serves as a protection for the eyelet wall but definitely prevents the escape of the thread back into the slot 6 once it has entered the eyelet 4. A further advantage in having the end of the member C inwardly of the eyelet opening is that any likelihood of the thread catching on the same as it passes from the eyelet is avoided.

In the eyelet 4 we dispose a brush member B which extends across the threading passage 5 and is fastened in the opposite wall of the shuttle body. This brush serves to tension the thread during the run of the shuttle and also acts as a further guard to prevent the escape of the thread from the shuttle eye once the same is in place therein.

In the threading operation with a left hand wound bobbin, the thread is carried from the end of the bobbin forwardly into the slot 11' in the end of the shuttle which as stated above is approximately in alinement with the end of the bobbin. Under tension the thread slips over and under the portion A⁴ of the member A and under the forward end B³ of the member B and lies on the shoulder until it enters the threading slot 6. As it is drawn

through this slot into the eyelet 4 that portion just entering the shuttle throat is deflected to the outer side of the shoulder 7 and slips over the edge thereof under the guidance of the portion A¹ of the guide A and enters the slot 9 where it engages the snubbing post 8 and passes into the fibres of the brush B, the outer end extending through the eyelet opening 4.

10 With a right hand wound bobbin, the thread is led forward into the slot 11' as with a left hand wound bobbin and during such passage it slips beneath the portion R² to lie over the shoulder 7. As it slips from the slot 15 5 to the slot 6, it is deflected over the edge of the shoulder and is guided into the slot 9 by the guide S which maintains it in said slot 9 during the run of the shuttle.

10 The peculiar design and arrangement of 20 the thread guide and guards in our shuttle permits a readier and more satisfactory threading of the shuttle than anything which has heretofore been employed in this art.

25 Modifications in the design of the shuttle nose, the arrangement and construction of the several guide and guard members and the means and manner of anchoring the same in the shuttle nose as well as the relation of each to the other may obviously be resorted to 30 without departing from the spirit of our invention if within the limits of the appended claims.

What we therefore claim and desire to secure by Letters Patent are:

35 1. In a shuttle, a bobbin, a throat forwardly thereof, a thread delivery eye and threading slots communicating therewith, a lateral shoulder in said throat, means forwardly of said threading slots disposed in the same horizontal plane as said shoulder to permit the thread during the threading action to be drawn straight forward in said throat in approximate alinement with said bobbin and prior to its passage to the threading eye.

40 2. In a shuttle, a bobbin, a throat forwardly thereof, a thread delivery eye and threading slots communicating therewith, a lateral shoulder in said throat, the wall of said shuttle forwardly of said threading slots being shaped to permit the thread during the threading action to be drawn straight forward over said shoulder in said throat in approximate alinement with said bobbin and prior to its passage to the threading eye.

45 3. In a shuttle, a bobbin, a throat forwardly thereof, a thread delivery eye and threading slots communicating therewith, the shuttle forwardly of said threading slots being shaped to permit the thread to be drawn straight forward in substantial alinement with the bobbin, a lateral shoulder in said throat in substantial alinement with said shaped portion of the shuttle, said thread being drawn thereover during the shuttle threading operation.

4. In a shuttle, a bobbin, a throat forwardly thereof, a thread delivery eye and threading slots communicating therewith, the shuttle forwardly of said threading slots being shaped to permit the thread to be drawn straight forward in substantial alinement with the bobbin, a lateral shoulder in said throat in substantial alinement with said shaped portion of the shuttle, said thread being drawn thereover during the shuttle threading operation, said shoulder being undercut to provide a thread passage into which the thread is led, as the thread turns from said forward motion to enter the delivery eye.

5. In a shuttle having a throat and a thread delivery eye, the shuttle wall opposite to and forward of said delivery eye being cut away to provide an overhang, a thread guide and guard mounted at its rear end in the floor of said throat and extending forwardly in said throat and having its other end anchored in the wall of said shuttle forwardly of said threading eye under said overhang, the thread being drawn over and under said guide during the threading of said shuttle and prior to the passage of the thread to the threading eye.

6. In a shuttle having a throat and a thread delivery eye, a lateral shoulder in said throat having a thread passage leading to said threading eye, a thread guide and guard mounted at its rear end in the floor of said throat outwardly of said shoulder and extending forwardly above said shoulder and having its other end anchored in the wall of said shuttle forwardly of said threading eye, the thread being drawn over and under said guide to travel over said shoulder during the threading of said shuttle and prior to the passage of the thread to the threading eye, said guide being spaced outwardly a sufficient distance from said shoulder to permit the passage of the thread therebetween as the same is drawn over said shoulder as it passes into the threading eye to lie in said passage in said shoulder when the shuttle is threaded.

7. In a shuttle having a throat and a thread delivery eye, a lateral shoulder extending into said throat from said shuttle wall having a threading slot leading to said threading eye, a thread guide and guard mounted at one end in the floor of said throat inwardly of said shoulder and extending forwardly above said shoulder and having its other end anchored in the wall of said shuttle forwardly of said threading eye, the thread being drawn over and under said guide to travel over said shoulder during the threading of said shuttle and prior to the passage of the thread to the threading eye as the thread is drawn toward the threading eye slipping over said shoulder to travel in said slot when the shuttle is threaded.

8. In a shuttle having a throat and a thread delivery eye, a wire thread guide and guard

5 mounted in said throat having one end mounted in the floor thereof and extending forwardly and anchored at its other end in the wall of said shuttle opposite to and beyond said threading eye, the wall of said shuttle adjacent said point of anchorage being cut away to provide an overhang.

9. In a shuttle having a throat and a thread delivery eye, a thread guide and guard in 10 said throat with one end mounted in the floor thereof, said shuttle wall being notched above said mounting, a loop in said guide adapted to lie in said notch to prevent slipping of the thread between the guide and the shuttle wall 15 during the threading of the shuttle, said guard extending forwardly beyond said loop and anchored in the wall of said shuttle beyond said threading eye.

10. In a shuttle having a throat and a 20 thread delivery eye, a thread guide and guard in said throat and having one end mounted in the floor thereof and extending forwardly and anchored at its other end in the wall of said shuttle opposite to and beyond said 25 threading eye, a second thread guide and guard having one end mounted on the top of the wall of the shuttle on its threading side and extending forwardly beyond said first 30 named guide and during a portion of its length partially overlying the same, said guides being separated to an extent sufficient to permit the passage of the thread therebetween, said second named guide being bent upon itself and extending backward as a 35 guide for said thread in its passage to the threading eye and being anchored in the shuttle wall adjacent said threading eye.

11. In a shuttle of the class described, having a bobbin, a throat forwardly thereof, a 40 thread delivery eye and threading slots comprising a forward slot leading to a point beyond the eye and a communicating slot leading back to the eye, the combination of a pair of laterally opposed guides, the shuttle wall 45 opposite to and forward of said delivery eye being shaped to define an overhang under which the forward ends of said guides are located, and a lateral shoulder extending into the shuttle throat and over which the thread 50 is adapted to travel after it passes over and under said guides and from which it is deflected into said throat as it passes from the forward slot through said communicating slot into the shuttle eye.

55. 12. In a shuttle of the class described, having a bobbin, a throat forwardly thereof, a thread delivery eye and threading slots comprising a forward slot leading to a point beyond the eye and a communicating slot leading 60 back to the eye, the combination of a pair of laterally opposed guides, one overlying the other, the shuttle wall opposite to and forward of said delivery eye being shaped to define an overhang under which 65 the forward ends of said guides are located,

and a lateral shoulder extending into the shuttle throat and over which the thread is adapted to travel after it passes over and under said guides and from which it is deflected into said throat as it passes from the 70 forward slot through said communicating slot into the shuttle eye.

13. In a shuttle of the class described, a bobbin, a throat forwardly thereof, a thread delivery eye and threading slots comprising a forward slot leading to a point beyond the eye and a communicating slot leading back to the eye, the combination of a pair of laterally opposed guides, the shuttle wall opposite to and forward of said delivery eye being shaped to define an overhang under which the forward ends of said guides are located, and a lateral shoulder extending into the shuttle throat and over which the thread is adapted to travel after it passes over and 80 under said guides.

14. In a shuttle, a bobbin, a throat forwardly thereof, a thread delivery eye and threading slots communicating therewith, a shoulder extending into said throat and having a lateral undercut communicating with said threading eye into which the thread is deflected as the same passes from said forward slot into said communicating slot to 85 said delivery eye.

15. In a shuttle, a bobbin, a throat forwardly thereof, a thread delivery eye and threading slots communicating therewith, a shoulder extending into said throat and having a lateral undercut communicating with said threading eye into which the thread is deflected as the same passes from said forward slot into said communicating slot to 90 said delivery eye and a guide preventing the escape of said thread from said slot during 100 the travel of the shuttle.

16. In a shuttle, a bobbin, a throat forwardly thereof, a thread delivery eye, a forward threading slot between the shuttle wall and said shoulder and extending forward of said delivery eye, and a communicating slot leading back to the eye, a lateral shoulder extending into said throat and over which the thread is adapted to lie during the threading action and prior to the passing of the thread from the forward slot into the slot leading to the eye, at which point the thread slips downwardly from said shoulder into said slot and a guard preventing escape of said thread from said slots.

17. In a shuttle, a bobbin, a throat forwardly thereof, a thread delivery eye, a lateral shoulder extending into said throat, a forward threading slot between the shuttle wall and said shoulder and extending forward of said delivery eye, and a communicating slot leading back to the eye, a lateral undercut in said shoulder into which said thread is adapted to be led as it passes through said communicating slot into said delivery eye.

and a guard preventing escape of said thread from said slots.

18. In a shuttle, a bobbin, a throat, forwardly thereof, a thread delivery eye and threading slots communicating therewith, the wall of said shuttle forwardly of said threading slot being cut away to provide an overhang and forwardly of said overhang being grooved to permit the thread during the threading action to be drawn straightforward in said throat in approximate alignment with said bobbin and prior to its passage to the threading eye.

19. In a shuttle, a bobbin, a throat forwardly thereof, a thread delivery eye, a lateral shoulder extending into said throat, a forward threading slot extending forward of said delivery eye and a communicating slot leading back to the eye, the shuttle wall opposite to and forward of said delivery eye being shaped to define an overhang, a groove in the shuttle wall forwardly of said overhang and in horizontal alignment with the top of said shoulder, said throat being led forward over said shoulder under said overhang and into said slot during the threading operation prior to its entry into said communicating slot and delivery eye.

20. In a shuttle, a bobbin, a throat forwardly thereof, a thread delivery eye and threading slots communicating therewith, the wall of said shuttle forwardly of said threading slot being cut away to provide an overhang and forwardly of said overhang being grooved to permit the thread during the threading action to be drawn straightforward in said throat in approximate alignment with said bobbin and prior to its passage to the threading eye, and a guide having its end lying underneath said overhang and over and under which the thread passes as it is drawn into said groove.

21. In a shuttle, a bobbin, a throat forwardly thereof, a thread delivery eye and threading slots communicating therewith, the wall of said shuttle forwardly of said threading slot being cut away to provide an overhang and forwardly of said overhang being grooved to permit the thread during the threading action to be drawn straightforward in said throat in approximate alignment with said bobbin and prior to its passage to the threading eye, and a pair of laterally opposed vertically spaced thread guides, one overlying the other and having their ends lying underneath said overhang and over and under which the thread passes as it is drawn into said groove.

22. In a shuttle having a throat and a thread delivery eye, a lateral shoulder extending into said throat, a thread guide and guard in said throat with one end mounted in the floor thereof rearwardly of said shoulder, a lateral undercut in said shoulder, said shuttle wall being notched above said

mounting of the guide and guard, a loop in said guide adapted to lie in said notch to prevent escape of the thread from said throat as the same is drawn over said shoulder and into said undercut during its passage to the delivery eye.

23. In a shuttle having a throat and a thread delivery eye, a thread guide and guard in said throat with one end mounted in the floor thereof, said shuttle wall being notched above said mounting, a loop in said guide adapted to lie in said notch to prevent slipping of the thread between the guide and the shuttle wall during the threading of the shuttle.

In testimony whereof we affix our signatures.
